CANOE YOKE

William E. Massicotte, Wawa, Ontario, Canada

Application June 8, 1951, Serial No. 230,461

11 Claims. (Cl. 9—1)

1

This invention comprises novel and useful improvements in a canoe yoke and more specifically pertains to improved means which may be readily attached to conventional canoes to facilitate and render more comfortable their portage upon the heads and shoulders of a person.

The primary object of this invention is to provide a portage yoke for canoes which shall be of a flexible, web-like construction; strong and sturdy in use and yet comfortable and convenient for the person portaging the canoe; and which shall be capable of compact folding into a small compass when not in use.

A still further object of the invention is to provide a portage yoke as set forth hereinbefore, which may be easily applied to conventional forms of canoes; will provide a cushioning carrying pad for the shoulders of a person to support the weight of the canoe thereon; shall conveniently encircle the neck of the carrier to assist in securely resting the canoe upon the shoulders of the wearer, and this regardless of which end of the canoe is placed forwardly.

Yet another object of the invention is to provide a hand grip construction which may be readily applied to conventional canoes to be employed in conjunction with the portage yoke to further assist the carrier in securely supporting the canoe upon his shoulders.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a top plan view showing a conventional canoe having the portage yoke and hand grip attachments of this invention applied thereto and shown in operative position for portaging a canoe;

Figure 2 is a vertical transverse sectional view taken substantially upon the plane indicated by the section line 2—2 of Figure 1, and illustrating the canoe in its inverted position for portaging by a person, the position of the person being indicated in dotted lines therein in order to depict the operation of the invention;

Figure 3 is a vertical longitudinal sectional detail view, upon an enlarged scale, taken substantially upon the plane indicated by the section line 3—3 of Figure 1 and showing certain structural features of the portage yoke of this invention;

Figure 4 is a vertical transverse sectional de-

tail view, taken upon an enlarged scale substantially upon the plane indicated by the section line 4—4 of Figure 1 and illustrating other structural details of the portage yoke of this invention;

Figure 5 is a perspective view of the skeleton or framework of the canoe yoke of this invention;

Figures 6 and 7 are enlarged perspective detail views of a portion of the side and gunwale of a canoe showing more clearly the structure of the hand grip attachment, these figures respectively showing the hand grip attachment locked in the inoperative and in the carrying position; and

Figure 8 is a fragmentary perspective detail view of a portion of the skeleton of the canoe yoke.

Referring now more specifically to the accompanying drawings, wherein like numerals designate similar parts throughout the various views, it will be seen that a conventional canoe is indicated generally by the numeral 10, this canoe including the usual gunwale construction consisting of an outer member 12 secured to the upper edge of the outside surface of the side wall 14 of the canoe, and further including an inner member 16 secured to the upper edge of the inside surface of the side wall of the canoe, being directly secured to the usual ribs 18 of the canoe construction. It is to this conventional canoe construction, just described, that this invention is particularly applicable, as shown by way of example in these drawings.

When it is necessary to transport canoes preparatory to placing the same in the water or subsequent to removing the canoe from the water, they are customarily carried in an inverted position upon the shoulders and head of the carrier, as indicated in Figure 2. When one person is transporting the canoe, it is usually somewhat difficult to comfortably support the gunwales of the canoe upon the shoulder of the carrier and also to evenly balance the canoe during this portage. The present invention envisions a flexible, pliable, comfortable carrying yoke which can be quickly attached to a conventional canoe whereby the weight of the canoe may be more comfortably supported upon the shoulders of the carrier; whereby the yoke will assist in preventing sliding movement of the canoe forwardly or rearwardly of the shoulders of the carrier; and wherein movable hand grip attachments are provided whereby the hands of the user may steady and support the weight of the canoe during its portage.

This attachment, consists of a canoe portage

yoke indicated generally by the numeral 20 together with a plurality of hand grip attachments which in their entirety are indicated generally by the numeral 22. As will be readily understood however in some instances it may be preferred to utilize the functions and services of the portage yoke independently of the hand grip attachments, or in other circumstances the independent use of the hand grip attachments may be preferred. In order to illustrate the manner in which the principles of this invention may be utilized to the fullest extent, the application of both of these elements to a conventional canoe has been illustrated and described hereinafter.

Referring first to Figure 5, it will be seen that the canoe portage yoke 20 includes a rod like, hinged or articulated skeletal framework construction. This construction includes an H-shaped neck portion 24, to the opposite sides of which are hingedly connected shoulder portions 26. Fasteners, to be described hereinafter, are hingedly or pivotally connected to each of the shoulder portions and constitute a means whereby the latter and consequently the canoe yoke, may be removably secured to the gunwales of a canoe.

Referring first to the neck portion, it will be seen that the latter consists of rod like members including a crossbar or cross-rod 28, terminating in loops or hooks 30 at its opposite ends, see Figure 8, which are pivoted and loosely and slidably embrace the side rods or side bar members 32 of the H-shaped neck portion. The H-shaped neck portion is further provided with a pair of U-shaped or arcuate reinforcing rods 34 which have their midportions abutted against opposite sides of the crossbar 28, and have their leg portions disposed alongside the side bars 32 and engaged at their extremities to the extremities of the side bars as by the hooked connections 36, as shown in Figure 5.

It is evident that the reinforcing rods 34 may be securely attached to the cross-rod 28 in various known manners. In some instances it may be preferred to weld or otherwise rigidly secure these members into a permanent assembly. One suitable manner, illustrated in Figure 3 of the drawings, comprises the provision of a flexible fastening at this point, comprising a winding 38 of a suitable fiber or wire material which is wound about each of the reinforcing rods 34 and also about the cross-rod 28 to securely attach these elements together but permit a limited relative swinging movement therebetween.

This framework of the H-shaped neck portion is preferably covered by a coating 40 of any suitable material such as webbing, lacing, canvas or the like. The purpose of this coating is both to enclose and protect the skeletal framework of the neck portion as well as to provide a cushioning pad which will render more comfortable engagement of the neck portion with the neck and shoulders of the user.

From Figure 1 it will be apparent that the neck portion is provided with arcuate recesses 42 disposed upon the opposite front and rear sides of the yoke. These recesses will comfortably encircle or embrace a portion of the neck of the user, to permit the shoulder portions of the yoke to rest comfortably upon the shoulders of the carrier. Once the device is attached to the canoe, it is obvious that either end of the canoe may be pointed forward and one of the recesses 42 will receive the neck portion of the user. This construction also permits the neck to be disposed

in either the forward or rearward recess 42 at the convenience and desires of the carrier, which permits the yoke to be attached to various portions of the canoe whereby the neck of the carrier may be disposed in either the forward or rearward recess.

This construction further facilitates the use of the yoke in pairs or in even greater numbers, so that the canoe may be portaged by two or more persons if desired.

Referring now again to Figure 5, it will be seen that the two shoulder portions 26 are of identical construction, each consisting of a preferably substantially rectangular rod like frame of which the previously mentioned side rods or side bars 32 of the H-shaped neck portion constitute one side. The opposite side of the shoulder portions consists of rods or bars 43 disposed in parallel relation to the rods 32, and forming the central portions of U-shaped members having parallel outwardly extending legs 44. The side members of the rectangular shoulder portions consist of integral, parallel side members 46 which are formed upon the ends of the rods 32, and at their extremities are pivoted as by hooks or eyelets 48 to the rods 43. Conveniently, a sleeve 50 may encircle each of the rods 43, and a somewhat similar sleeve 52 encircles each of the rods 32. However, this sleeve 52 is provided with a notched or cut-away portion 54 at its midpoint to receive the above mentioned pivot hook 30 of the crossbar 28. The sleeve 52 thus serves to restrain the crossbar 28 to a midposition between the ends of the bars 32 while permitting swivelling movement therebetween as will be apparent from Figure 8.

As so far described, it will now be apparent that the rectangular frames of the shoulder portions are pivoted to the H-shaped neck portion. Preferably a covering of any suitable nature, such as canvas, webbing or the like is secured upon the parallel sleeves 50 and 52 of the shoulder portions to form a resilient cushion or pad whereby the shoulder portions rest upon the shoulders of the canoe carrier.

Detachable fasteners are provided whereby the yoke may be secured to the gunwales of a canoe. These fasteners consist of bolts 56 having eyes or hooks 58 at one end thereof which are detachably secured in the eyelets 60 at the outer ends of the leg portions 44. The other ends of the bolts are threaded as at 62 to extend through suitable apertures in the gunwales of the canoe, fastening nuts 64 serve to detachably retain the yoke tightly stretched across the canoe transversely of the same and between the gunwales as shown in Figures 1 and 2. It is obviously intended that the yoke shall be stretched with sufficient tautness across the gunwales to support the canoe with a minimum deflection of the yoke upon the shoulders of the wearer and thus prevent uncomfortable impacts of the bottom of the canoe upon the head of the wearer.

From the foregoing it will be readily seen that the yoke may be easily attached to or removed from the canoe completely, wherein in some instances it may be preferred to merely disengage the fasteners at one side of the yoke and thus permit the yoke to be compactly folded against one side of the canoe when not in use. Suitable means may of course be provided for retaining the collapsed yoke in its compactly folded position if desired.

In addition to the yoke construction previously described, movable and adjustable hand grips

are provided to facilitate the portaging of the canoe. Referring now more specifically to Figures 6 and 7, it will be seen that these hand grips consist of four hand grip attachments, two being provided upon each gunwale on opposite sides of the yoke attached thereto. Each of these hand grip attachments consists of a short lever or handle 66 mounted upon the top surface of the outer gunwale 12 and pivoted thereto as by a pivot pin 68 which may be a bolt, rivet or the like. This hand grip lever is thus mounted for pivoting movement upon the gunwale and may be selectively disposed in the position shown in Figure 6 whereby the handle is retracted into an out of the way position, or may be pivoted inwardly into a position extending transversely and laterally of the gunwale but inwardly of the boat into an operative position. A locking means is provided for selectively retaining the hand grip members in either their retracted or their operative positions. This locking means comprises a bracket 70 mounted upon the inner gunwale member 16 as by fastening screws or the like 72, and having an upstanding portion 74 constituting a stop which is adapted to be engaged by the hand grip lever when the latter is in its operative position, and form a stop abutment for the same. The brackets further include an overhanging retaining terminal portion 76 which is adapted to overlie the top surface of the lever in its operative position and further brace and reinforce the lever against the strains imparted thereto during the portaging of the canoe.

A locking pin is rotatably and slidably secured to the gunwale construction as by a fastening bracket 78 secured to the inner surface of the inner gunwale member below the upper edges thereof as by fastening bolts 80. This bracket includes a vertically disposed cylindrical bearing portion 82 through which is slidably and rotatably received the axle portion 84 of the locking pin. One end of this axle below the bracket is preferably provided with a looped or eyed portion 86 constituting a hand grip by means of which the device may be manipulated, a compression spring 88 being disposed between this eye and between the bearing portion 82 as shown. This spring normally urges the axle downwardly through the bearing, to thus urge the inturned extremity 90 of the locking pin to a locking recess 92 forming the top surface of the hand grip member 66. It will thus be apparent that the spring 88 will retain the locking pin in the recess when the hand grip member is disposed in either its retracted or operative position as shown in Figures 6 and 7. Obviously, when it is desired to swing the handle 66 from its operative to its inoperative positions, or vice versa, the locking pin is released from the locking recess 92 and allowed to slide through the fastening bracket 78 until the inturned extremity 90 of the locking pin is disposed beneath the upper edge of the gunwale member 16.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be

resorted to, falling within the scope of the appended claims.

Having described the invention, what is claimed as new is:

5. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said neck portion having opposing arcuate neck encircling recesses.
10. 2. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said neck portion having opposing arcuate neck encircling recesses.
15. 3. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion.
20. 4. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, each shoulder portion including a rectangular rod-like frame, a sheet-like covering secured upon said last mentioned frame.
25. 5. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
30. 6. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
35. 7. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
40. 8. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
45. 9. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
50. 10. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
55. 11. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
60. 12. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
65. 13. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof.
70. 14. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof, retaining sleeves surrounding each of the side rods of the member and the
75. 15. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame being hingedly connected to opposite ends of said neck portion, said neck portion comprising an H-shaped rod-like member, arcuate reinforcing rods secured to each side of the cross rod of said member and to the parallel side rods thereof, retaining sleeves surrounding each of the side rods of the member and the

adjacent side rod of the adjacent rectangular frame for hingedly connecting the same.

6. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame including rectangular frames hingedly connected to opposite ends of said neck portion, said neck portion comprising an H-shaped rod-like member, arcuate reinforcing rods secured to each side of the cross rod of said member and to the parallel side rods thereof, retaining sleeves surrounding each of the side rods of the member and the adjacent side rod of the adjacent rectangular frame for hingedly connecting the same, the cross rod of the member being pivotally connected to the side rods thereof.

7. A canoe portage yoke comprising a flexible supporting frame, means for connecting said frame to the gunwales of a canoe in a position to extend transversely therebetween, said frame having shoulder portions with a recessed neck portion therebetween, said shoulder portions being adapted to rest upon the shoulders and the neck portion to embrace the neck of the carrier when a canoe is supported in inverted position upon the shoulder of the carrier, said shoulder portions of said frame including rectangular frames hingedly connected to opposite ends of said neck portion, said neck portion comprising an H-shaped rod-like member, arcuate reinforcing rods secured to each side of the cross rod of said member and to the parallel side rods thereof, retaining sleeves surrounding each of the side rods of the member and the adjacent side rod of the adjacent rectangular frame for hingedly connecting the same, the cross rod of the member being pivotally connected to the side rods thereof, said sleeves engaging the pivotal connection and pre-

45

venting longitudinal displacement of the cross rod upon the side rods.

8. In combination with a canoe having gunwales thereon, means for portaging the canoe comprising hand grips swingably mounted upon said gunwales, lock means for selectively securing said hand grips against movement in positions extending laterally inwardly from the gunwales and parallel to the gunwales, said lock means including a locking member slidably and rotatably mounted on the gunwale on an axis perpendicular to the plane of movement of the hand grips and retaining means on the locking member for positively engaging the hand grip in each of its positions.

9. The combination of claim 8, wherein each of said hand grips has a locking recess disposed therein.

10. The combination of claim 9, wherein the locking member comprises a looped portion at one end and a hooked portion at the other end, said hooked portion having an intermediate section parallel to the plane of movement of the hand grip and an end section perpendicular to the intermediate section, which end section is engageable in the locking recess in each of said hand grips.

11. The combination of claim 10, including resilient means provided on the locking member urging the locking member into engagement with each of said hand grips.

WILLIAM E. MASSICOTTE.
